UNITED STATES PATENT OFFICE.

HAROLD L. POST, OF APPLETON, WISCONSIN.

BASKET-BALL GAME.

1,407,215.

Specification of Letters Patent. Patented Feb. 21, 1922.

Application filed April 16, 1920. Serial No. 374,287.

To all whom it may concern:

Be it known that I, HAROLD L. POST, a citizen of the United States, and resident of Appleton, in the county of Outagamie and 5 State of Wisconsin, have invented a new and useful Improvement in a Basket-Ball Game, of which the following is a specification.

The object of my invention is to provide a novel parlor game approximating the sport 10 known as basket ball. I attain the object of my invention by the device shown in the accompanying drawings, in which—

Figure 1 is a side elevation of the game;

Fig. 2 is a top plan;

Fig. 3 is a detail view, partly in section and partly in elevation showing the means 15 for supporting members 7;

Fig. 4 is a detail vertical sectional view of the means for mounting member 2.

20 Fig. 5 is a detail of a modified basket arrangement; and

Fig. 6 is a detail elevational view of member 18 which normally closes opening 17.

Like numerals designate like parts in each 25 of the views.

Referring to the accompanying drawings I provide a baseboard 1, and end boards 2, pivotally mounted on rods 3 which are mounted on metal braces 4 which are secured to the baseboard 1, as illustrated in the drawings. Each of the braces 4 has a side 5 which limits the rearward movement of end board 2, so that they will not move backward beyond a substantially vertical 30 position. The end boards 2 are provided with spaced cylindrical sockets 6 adapted to receive the ends of four rods 7, attached to which rods I provide suitable netting 8 as illustrated in Fig. 1. I provide miniature baskets 10 of netting or other suitable material attached to rings 9 and adapted to be suitably fastened to end board 2 in horizontal position as shown in Fig. 2; or to be secured in vertical position about the 35 openings 17 as shown in Fig. 5, in which latter case a modified type of game is played. I provide suitable playing sticks or rods 11, to approximately the central portion of which are attached miniature figures 12, each of which carries a ring 13 having an opening 14, said opening 14 being of less size than the miniature basketball 15. The rings 13 carried by these miniature figures 12 are utilized in throwing the ball toward 40 the basket attached to the end board at the other end of the "field."

Midway of the base board 1 I provide suitable posts or stops 16 to limit each of the playing sticks or rods 11 to their own half of the field. In each of the end boards 60 is an opening 17 as shown in Figs. 2, 5, and 6 around which the ring 9 of the basket may be secured by suitable pivoted fasteners 19, when a modified type of game is to be played. Ordinarily, however, the 65 openings 17 are closed by the discs 18 which are held in place by the fasteners 19, the baskets 10 then being supported within the end board 2 as shown in Fig. 2 instead of from their outer portions as shown in Fig. 70 5. The playing sticks 11 are grasped in one hand by the players and the manikin figures moved about to catch and throw the ball somewhat after the fashion of a tennis racket, the object being to land the ball in 75 the basket at the other end of the "field." Each player is limited to one half of the entire field by reason of the posts 16. Both players seek to get the ball into the circular opening 14 of the ring 13 carried by the 80 miniature figure 12 attached to the playing stick 11 and manipulate the stick so that the figure will lie flat on the base board and scoop up the ball. By giving a twist to the stick the ball may be thrown across the 85 field where the opposing player will seek to catch it and land it in the opposing basket. The playing sticks are long enough so that the player cannot operate in the other's field except to tilt the manikin figure over to get 90 the ball back to his field. The rules governing the game may closely approximate those governing the sport of basketball.

In the modified form of the game in which the baskets are disposed outside the end 95 board where they are supported by fasteners 19, not so much skill in playing the game is required as in the disposition of the baskets shown in Fig. 2, but the modified form of the game has more action and is more exciting. 100

By removing rods 7 from sockets 6 the end boards 2 may be turned down so as to lie flat on baseboard 1, and the device thus disposed in the most compact form for the purpose of packing and transportation. 105

What I claim is:

1. In a game apparatus, the combination of a baseboard, inwardly foldable endboards, the endboards having opposite openings, baskets adapted to be secured over the exterior of the openings, upper and lower rods removably mounted on either side of the

110

115

baseboard and supporting walls of netting in a spaced position above the top surface of the baseboard to permit of operating a playing implement on the baseboard and under the members to which the netting is attached, the aforesaid lower rod being positioned sufficiently distant from the baseboard to provide a continuous free space for the entire length of the baseboard for the free operation of a playing implement thereunder.

2. As a new article of manufacture for use in a game of the class described, a playing member comprising a playing stick, a manikin upright playing member rigidly attached thereto and a ring carried by the aforesaid member, said ring having an opening of less size than the ball used in playing the game.

3. In combination with the apparatus described in claim 1, pivoted fasteners attached to the exterior of the endboards and releasably securing the baskets over the

openings in the endboards, disks insertable in said openings to permit of modifying the structure of the game apparatus, and means for supporting the baskets on the inner side of the respective endboards, substantially as shown.

4. In a game apparatus, the combination of a baseboard, inwardly foldable endboards, the endboards having opposite openings, baskets adjacent the openings and mounted on the end-boards, upper and lower rods removably mounted on either side of the baseboard and supporting walls of netting in a spaced position above the top surface of the baseboard to permit of operating a playing implement on the baseboard, and end members to which the netting is attached, the aforesaid lower rod being positioned sufficiently distant from the baseboard to provide a continuous free space for the entire length of the baseboard for the free operation of a playing implement thereunder.
